UNITED STATES PATENT OFFICE

HOWARD SELLERS WORRELL, OF ARDMORE, PENNSYLVANIA, ASSIGNOR TO DICTAPHONE CORPORATION, OF BRIDGEPORT, CONNECTICUT, A CORPORATION OF NEW YORK

PHONOGRAPHIC RECORDING

Application filed December 3, 1925, Serial No. 72,904. Renewed April 17, 1929.

This invention relates to phonographs, and more particularly to improved methods and means for making phonographic records.

In the art of recording sounds, it has been proposed that a stylus operating diaphragm be actuated electromagnetically to translate current fluctuations corresponding to sound waves into mechanical movements for engraving the surface of a waxy record in accordance with such sound waves. It has also been proposed to discard the diaphragm and provide the recording stylus with means whereby it is directly operated by an electromagnet.

Both these proposals are predicated upon the use of an electromagnet with an armature and in such devices, difficulty is usually experienced in adjusting the armature properly to operate. For, as is well known, the pull of an electromagnet upon its armature varies with distance between the armature and the core of the electromagnet. Consequently, a slight variation in this distance might render the device practically inoperative, and hence, it is necessary to very carefully and accurately adjust the position of the armature with respect to the electromagnet core.

An object of this invention is to avoid these difficulties and this is accomplished by utilizing a solenoid and core instead of an electromagnet and armature for the actuation of the stylus. The use of a solenoid is advantageous since the air gap or space between the actuating coil and the core may be made substantially invariable.

Another difficulty heretofore experienced with electrical recording has been in the accommodation of the recording stylus to records of different thicknesses, it having been found necessary to move the electromagnet toward and from the record bodily to accommodate for the differences in diameters of the records between a new record and one which is practically consumed by reshaving. Another difficulty encountered was that of making the stylus properly follow the record in the ordinary recording operation, for it is known that all records are not exactly concentric. Therefore, provision must be

made for a small, yet important, rise and fall of the recording stylus during the rotation of the record.

To permit these two results to be obtained, a certain amount of weight was believed to be necessary and was employed to hold the stylus in proper operating position. Yet it was found that when the weight was made sufficiently heavy to do this, the parts had so much inertia as to prevent them from functioning properly.

These difficulties have been overcome by the present invention by employing electrical means for maintaining the stylus in proper recording position at the proper time.

Accordingly, the preferred embodiment of this invention may comprise a solenoid which itself operates to produce the recording movements of the stylus, and which, actuated by the carrier current used in the electrical transmission of sound to be recorded, moves the recording stylus into recording contact with the record and maintains such contact during the recording operation.

This feature also avoids another difficulty heretofore experienced in recording sound by either electrical or mechanical means, and that is the necessity of providing special mechanism for raising the stylus from the record surface when it is not desired to record, or when it is desired to do something else, for instance, when reproducing or when removing the record from the machine. This difficulty is obviated by the present invention because biasing means may be provided for returning the stylus to inoperative position out of engagement with the record so soon as the carrier current for the electrically transmitted sound ceases.

Another important feature of the present invention is the provision of improved means for mounting the stylus and its actuating parts, for, according to the present invention, the stylus is mounted on knife edges and the actuating link is also mounted on knife edges so as to reduce to a minimum the friction between these relatively moving parts and stationary parts which support them.

Other improvements and advantages will hereinafter appear.

In the accompanying drawing, which illustrates one form of this invention, that at present preferred—

Figure 1 is a sectional view through a phonograph made in accordance with this invention.

Fig. 2 is a top plan view of recording and reproducing mechanism shown in Fig. 1.

Fig. 3 is a view showing the electric recording mechanism shown in Fig. 1, showing the parts in the positions they assume during recording.

Fig. 4 is a diagrammatic view, showing improved means for operating electric recording devices.

As shown in the accompanying drawing, the phonograph comprises a base 10 having an upright 11 which supports a mandrel 12 for a record 13. Mounted on the base 10 are transverse guide rods 14 which support a carriage 15 for movement across the machine. The carriage 15 may be provided with the usual or conventional sound-box 16 having a reproducing stylus 17 for reproducing sounds recorded on the record 13. This reproducing stylus 17 is mounted on a holder 18 pivotally mounted on a weighted lever 19, and the stylus holder 18 is connected by a wire or link 20 to a diaphragm 21. Preferably, this sound-box 16 fits an opening 22 provided in the carriage adapted to receive 16.

According to the present invention, the recording mechanism preferably comprises a coil 23 mounted on a base 24 removably fitting an opening 25 provided in the carriage 15. The coil 23 is not provided with a magnetic core, but, of course, may be wound upon a fibrous core or other non-magnetic core, or it may be wound on a core which is later removed from the coil, whereupon the wires of the coil may be held together by a sizing material if desired.

The recording stylus 26, according to the present invention, is mounted on a stylus holder 27 whose forward end is forked (see Fig. 2) to provide a pair of arms 28 in which there is inserted a transversely disposed knife-edge bar 29. This knife-edge bar 29 engages a depending lug 30 which is provided at its lower end with a knife-edge receiving portion, as shown.

To actuate the stylus 26 and its holder 27 to record sound vibrations and to move the stylus 26 into record engaging or recording positions on records of different thicknesses, the stylus holder 27 is connected to a rod or core 31 which passes through the hollow center of the coil 23. This rod 31 is preferably made of iron so as to be acted upon magnetically by the magnetic field produced by the coil 23. The connections between the rod 31 and the stylus holder 27 preferably comprise a transverse knife-edge bar 32 set in forked arms 33 of the rearward end of the stylus holder 27 and a knife-edge receiving notch

34 provided on the rod 31, preferably near its end.

The stylus holder 27 is held in engagement with its supporting lug 30 and in engagement with the rod 31 by a spring 35 which exerts pressure rearwardly on the rod 31 and tends to draw the stylus holder 27 rearwardly through the engagement of the knife-edge receiving notch 34 with the knife-edge bar 32, and hence, draws the knife-edge bar 29 firmly against the lug 30 which acts as a fulcrum for the stylus holder.

At its upper end, the rod 31 may be guided by any suitable means which will tend to cause the rod to have a movement within the coil 23 as near parallel to the axis of the coil as practicable, and yet which will not increase or add appreciably to the friction of the moving parts of the device.

This means, according to the present invention, preferably comprises a knife-edge bar 36 having a knife-edge in engagement with a notch 37 in the rod 31 and a knife-edge in engagement with a notch 38 in a part connected to the head 24 in some suitable way. The upper end of the rod 31 may be guided further by means of a spring 39 attached to the upper end of the rod and also attached to a screw 40 adjustable up-and-down by means of a nut 41 in a bracket 42 so as to increase or decrease the tension or biasing effect of the spring 39, as desired under particular conditions.

When no current is being supplied to the coil 23, the spring 39 by its biasing action, maintains the rod 31 and stylus holder 27 in inoperative positions, those shown in Fig. 1, where the recording stylus 26 is out of engagement with the record. However, as soon as the supply current or carrying current of a circuit containing the coil 23 is allowed to become effective, it tends, by the well known principle of the solenoid, to centralize the rod 31 with respect of the coil 23. Since the part of the rod 31 protruding beyond the upper end of the coil 23 exceeds in length that part of the rod which protrudes below the lower end of the coil 23, the tendency of the carrier or supply current is to draw the rod 31 downwardly. In this position, the stylus 26 is pressed against the record with a force which is substantially the same whether a thick or thin record is used. When the carrier current is varied in accordance with sound vibrations, or when it has superposed upon it a modulating current, the recording stylus 26 is vibrated in accordance with the sound vibrations changing or modulating the carrier current. Hence, the rod 31 and stylus 26 are vibrated by the solenoid coil 23 to cause a groove, varying in depth with the characteristics of sound, to be engraved upon the waxy record surface.

It will thus be seen that only three moving parts are used and that these may be made ex-

tremely light so as to have very little, if any, appreciable inertia. Hence, the vibrating movements of the stylus holder will be substantially in accordance with the sound to be recorded, and by this means, the sound record will be faithful and clear, and will have sufficient amplitude to reproduce with the desired volume.

In order that the device may operate with greater certainty and so that the sound recorded will have sufficient volume under all conditions, the present invention proposes making the rod 31 a part of a magnetic circuit. This magnetic circuit is preferably excited by a coil 42 placed around a permanent magnet 43 whose one arm 44 comprises the lug 30 which supports the stylus holder and whose other arm 45 is engaged by the knife-bar 36 for the upper end of the rod 31.

Preferably, the current passing through the coil 42 is steady or non-fluctuating, that is to say, is separate and distinct from the current which is varied or modulated by the sound to be recorded. The magnetic circuit of the magnet 43 is completed through the knife-bar 36, rod 31 and stylus holder 27, all of which are preferably made of iron or other magnetic material so as to constitute a free path for the magnetism.

In Fig. 4, there is shown improved electrical means for operating the recording apparatus shown in Figs. 1 to 3. In this circuit a telephone transmitter 50 is connected by a wire 51 through the primary 52 of an induction coil 53 and a wire 54 to one side of a battery 55, while a wire 56 from the transmitter 50 is connected to the other side of the battery 55 through a switch 57 which, when closed, completes the supply current circuit to the transmitter and the latter is thus made operative. At the same time, that is, when the switch 57 is closed, current from the battery 55 is caused to flow through the solenoid coil 23 so that the stylus 26 will be brought into engagement with the record surface in the manner above explained. This is accomplished by connecting a wire 58 leading from the coil 23 to the induction coil secondary 57 which is connected by wires 60 and 61 to the switch 59 leading to the battery 55. The other wire 62 of the coil 23 is connected to the wire 51 which leads to the other side of the battery 55 through the primary 52 of the induction coil.

When the switch 57 is closed and sound waves are impressed upon the transmitter 50, the current flowing through the primary 52 of the induction coil is caused to alternate or fluctuate by the operation of the transmitter, and this alternating current causes an alternating or voice current which is increased in strength or the electromotive force is increased by the operation of the induction coil to be induced in the secondary 59. This voice current is impressed upon the solenoid coil 23

by connections between the secondary 59 of the induction coil 53 and the solenoid coil 23 which consists of the wire 58 leading from the coil 23 to one side of the secondary 59 and a wire 63 leading to a condenser 64 whose other side is connected to the wire 62 leading to the coil 23.

It will therefore be seen that the present invention comprises means for increasing the strength of the electromotive force of the voice current through the operation of an induction coil and yet permits or causes the solenoid coil 23 to be normally energized by the battery current so as to cause the stylus to be moved to and held in operative position by the operation of the switch 57.

In cases where the rod 31 is made to form parts of a closed magnetic circuit, as by the provision of the coil 42 and magnet 44, the system also includes a wire 65 connecting one side of the coil 42 with one side of the battery 55 and a wire 66 connecting the other side of the coil 52 with the wire 61 which leads to the switch 57 connected to the other side of the battery 55. Hence, when the switch 57 is open, both the coil 23 and the coil 42 are rendered inoperative.

Variations and modifications may be made within the scope of this invention and portions of the improvements may be used without others.

Having described the invention, what is claimed as new and for which it is desired to obtain Letters Patent, is:

1. A phonographic recording device comprising recording means for engaging a record, and a solenoid connected to said recording means for bringing the recording means to recording position, and to actuate the recording means in its recording position, said solenoid being in circuit with a telephone transmitter and vibrating said recording means in accordance with variations in said circuit caused by said telephone transmitter.

2. A phonographic recording device comprising a carriage, recording means on the carriage to engage a record, means on the carriage tending to normally keep said recording means inoperative, and electrically operated means for moving said recording means independently of the carriage into operative position.

3. A phonographic recording device comprising a stylus; electrical means actuated by telephonic carrier current for maintaining the stylus in recording position; and means for impressing upon said electrical means voice or signal currents which operate said electrical means to vibrate said stylus for recording.

4. A phonographic recording device comprising a stylus; a solenoid actuated by telephonic carrier current for maintaining the stylus in recording position; and means for impressing on said solenoid voice or signal

currents which operate said solenoid to vibrate said stylus for recording.

5. A phonographic recording device comprising a stylus; electrical means actuated by telephonic carrier current for maintaining the stylus in recording position; means for producing voice or signal currents; means for transforming said voice or signal currents; and means for impressing on the said 10 electrical means the transformed voice or signal currents which operate said electrical means to vibrate said stylus for recording.

6. A phonographic recording device comprising a stylus; a solenoid actuated by telephonic carrier current for maintaining the stylus in recording position; means for producing voice or signal currents; an induction device for transforming said voice or signal currents; and means for impressing on 20 the said solenoid the transformed voice or signal currents which operate said solenoid to vibrate said stylus for recording.

7. A phonographic recording device comprising in combination, recording means for 25 engaging a record, a solenoid having a movable member operatively connected with said recording means for bringing the recording means to recording position and to actuate said recording means in its recording position, said solenoid being in circuit with a 30 telephone transmitter and vibrating said recording means in accordance with variations in said circuit caused by said transmitter, a separate source of magnetic flux, and means to connect said source to said movable member to maintain magnetism in said movable member.

8. A phonographic recording device comprising in combination, recording means for 40 engaging a record, a solenoid for holding said recording means in contact with said record and for vibrating said recording means in accordance with the sound vibrations to be recorded, said solenoid comprising a movable 45 magnetic core responsive to magnetic vibrations caused by voice currents impressed upon said solenoid, and an electromagnet including said movable core as a part of its magnetic structure.

50 9. The herein described method of electrically recording sound which consists in causing carrier current to maintain in record engaging position a normally inoperative stylus of an electrically responsive device, and 55 causing said stylus to be vibrated as the result of voice or signal currents superimposed upon said electrically responsive device.

10. A phonographic recording system comprising a transmitter; an inductive coupler; 60 a battery; an electrically operated recorder comprising a stylus; means for feeding direct current from said battery to said recorder to maintain said recorder energized and the stylus thereof in recording position; means 65 for feeding direct current to said transmit-

ter; means for feeding voice or signal current produced by the transmitter to the primary of the inductive coupler; and means for feeding voice or signal current induced in the secondary of said inductance coupler to the recorder to vibrate the stylus of the recorder.

Signed at Bridgeport, in the county of Fairfield and State of Connecticut, this 2nd day of December, 1925.
